W. J. PERRY

PIPE CASTING MACHINE

Filed April 7, 1921

Inventor.

*William J. Perry,
by H. J. Denman, atty.*

UNITED STATES PATENT OFFICE.

WILLIAM J. PERRY, OF TORONTO, ONTARIO, CANADA.

PIPE-CASTING MACHINE.

Application filed April 7, 1921. Serial No. 459,403.

To all whom it may concern:

Be it known that I, WILLIAM J. PERRY, a subject of the King of Great Britain, and resident of the city of Toronto, county of 5 York, Province of Ontario, in the Dominion of Canada, have invented certain new and useful Improvements in Pipe-Casting Machines, described in the following specification and illustrated in the accompanying 10 drawings, that form part of the same.

The principal objects of the invention are to devise an improved method of feeding the molten metal to a rotating cylindrical mould, enabling the use of a sand lined 15 mould and retaining a uniform surface thereby producing a pipe of uniform thickness and texture.

The principal feature of the invention consists in the arrangement of a rotating 20 member at the delivery end of the spout for pouring the metal whereby a rotative motion is imparted to the metal as it flows from the spout.

The drawing represents a longitudinal 25 section of a pipe casting machine embodying this invention.

Centrifugal pipe casting machines of various forms have been devised but up to the present it has not been found practicable 30 to use sand lined moulds on account of the washing effect of the flowing metal and in using metal moulds the metal of the pipe is chilled by contact with the metal surface. The result of chilling the metal as it contacts 35 with the metal mould is the production of a pipe of ununiform texture as it is well known that chilling of cast iron produces a short grained crystalline structure which naturally varies considerably in the length 40 of the pipe.

In the structure herein shown the mould casing 1 is rotatably supported on rollers 2 and 3 and this casing is lined with a suitable moulding sand 4 which is swept in a 45 suitable manner to form the desired external shape for the pipe. In using a sand lining a spigot end may be formed as it will pull out of the sand in removing the finished pipe.

50 A pouring spout 5 of tubular form is rigidly supported at one end on a suitable travelling carriage 6, and is adapted to extend axially into the mould. The spout is

lined with a refractory lining 7 and is provided with a hopper 8 into which the metal 55 is poured from the ladle 9 arranged upon the carriage.

A tubular member 10 encircles the spout 5, being supported upon suitable anti-friction bearings 11 and 12 and this member extends beyond the pouring end of the spout and is provided with a refractory lining 13 which forms a continuation of the spout and flares outwardly. The terminal edge 60 of the rotatable spout member is of slightly less diameter than the inner wall of the pipe to be cast so that the metal will be delivered as close to the sand lining 4 as possible.

The member 10 is rotated in any suitable manner, a pulley 14 being shown arranged 65 at the end adjacent to the hopper and this is driven by a belt 15 extending around a pulley 16 carried on a shaft 17 journalled on the carriage 6 and suitably driven.

In the operation of this device, the mould 70 is first prepared and the carriage is then operated to extend the pouring spout into the mould to its farther end.

The member 10 is caused to rotate at a suitable speed preferably corresponding to 75 the speed of rotation of the mould and the metal is then poured from the ladle into the spout 5. As the metal leaves the end of the spout 5 it flows over the rotating portion 80 13 of the member 10 and is thus directed with a whirling movement at a corresponding speed of rotation to that of the mould. The delivery thus achieved avoids rupture 85 of the surface of the sand lining and the flow will be uniform and smooth as the carriage 6 is operated to move the spout at the desired speed the length of the mould.

The pipe thus formed will be moulded in sand and will not be chilled, consequently 90 the texture of the metal will have a tough fibrous texture which is extremely desirable.

What I claim as my invention is:—

1. In a pipe casting machine, the combination with a rotating mould and a non-rotatable pouring spout relatively movable 100 longitudinally, of a rotatable member arranged at the delivery end of the spout adapted to impart a rotative movement to the metal flowing from the end of the spout.

2. In a pipe casting machine, the combination with a rotating mould and a non- 105

rotatable pouring spout relatively movable longitudinally, of a tubular member rotatably encircling the spout and extending beyond the delivery end thereof, and means for rotating said tubular member.

3. In a pipe casting machine, the combination with a rotating mould and a pouring spout relatively movable longitudinally, of a tubular member encircling said spout and spaced therefrom and extending beyond the delivery end of said spout, anti-friction bearings supporting said tubular member on said spout, and means arranged adjacent to

the receiving end of the spout for rotating said tubular member.

4. In a pipe casing machine, the combination with a rotating mould and a pouring spout relatively movable longitudinally, of a tubular member rotatably encircling the spout and extending beyond the delivery end thereof and having a flaring refractory lining to receive the metal from the delivery end of the spout, and means arranged at the opposite end of said tubular member for imparting rotation thereto.

WILLIAM J. PERRY.
